DISPENSING DEVICE

Constante Carlos Dajoz and René Eduardo
Dubois, Buenos Aires, ArgentinaApplication September 26, 1940; Serial No. 358,430
In Argentina August 21, 1940

7 Claims. (Cl. 312—78)

The present invention relates to dispensing devices, and in particular to a device for dispensing toothpicks under highly hygienic conditions.

The wooden toothpicks commercially available at the present time may be roughly divided into two classes, namely the round or machine finished type and the flat or rough-split type. The former are spindle-shape bodies of uniform size and shape, and as the ends are thinner than the middle and, therefore, are separated when the toothpicks are in bundles, the round type readily lends itself to automatic dispensing and devices for this purpose have already been proposed.

Toothpicks of the flat type, however, are subject to variations as to length, width and thickness, have rough surfaces and pack together tightly when bundled, so that the dispensing devices designed for the better, round type have been found quite unsuitable for the flat type, and up to the present no successful dispensing device for flat type toothpicks is known.

It will be obvious that the flat type of toothpick is much cheaper than the round, and in spite of its lack of finish, is more suitable for people whose teeth are so closely set as to make the use of the round type difficult or positively harmful to the gums. For these reasons, the flat type has found considerable favour among restaurant proprietors and the like, but owing to the lack of a suitable closed dispensing device, the flat toothpicks are usually placed in open glass or the like containers or tubs, and are thus exposed to all the dirt, dust, germs and similar pollutions which they are likely to receive from the atmosphere or from the hands of customers or waiters.

The principal object of our invention is, therefore, to provide a dispensing device adapted particularly to dispense flat type toothpicks, and comprising a substantially completely enclosed magazine for containing the toothpicks and means operable from outside the device for dispensing the toothpicks one by one through a narrow orifice communicating with the magazine.

A further object of the present invention is to provide a dispensing device adapted particularly, though not exclusively, to dispense flat type toothpicks and comprising a housing including a mechanism chamber containing reciprocable actuating and operative members spring urged to a normal position, and a magazine chamber which is preferably separable and contains guide means against which a bundle of toothpicks is adapted to be yieldably held, and compression

means adapted to be actuated by said mechanism to compress the bundle, said mechanism comprising a dispensing finger adapted to move a single toothpick through a dispensing orifice in a lid portion of said housing.

Other objects and advantages of our invention will become apparent in the course of the detailed description.

In the drawings:

102 Fig. 1 is a perspective view of one embodiment of our novel dispensing device.

Fig. 2 is a plan view of the device of Fig. 1 with the lid removed.

Fig. 3 is a section along the line III—III of Fig. 2.

Fig. 4 is a perspective view of a separable magazine chamber.

Fig. 5 is a perspective view of a mechanism chamber with the lid removed.

Fig. 6 is a perspective view of a preferred form of actuating and operative members, and

Fig. 7 is a perspective view showing the underside of a lid portion.

With reference to the drawings, our novel toothpick dispensing device comprises a housing 10, preferably with rounded ends as shown, containing a magazine chamber 12 and a mechanism chamber 14 and having a lid portion 15, a bottom wall 16, 16' and side walls 17, 17'.

In the embodiment illustrated, the magazine chamber is made separable and is defined by the side wall 17', a base portion 18, best seen in Fig. 3, and upper and lower angular guide members 20, 22. The mechanism chamber 14 is defined by the side wall 17, the bottom wall 16 and the lid 15. The bottom wall 16 has a portion 16' projecting beyond the side wall 17 and extending to the side wall 17' so as to underlie the base 18 of the magazine chamber in the assembled condition of the device.

The angular guide members 20, 22 are secured as by soldering at the ends of their arms to the inner face of the side wall 17' of the magazine chamber 12 in superposed spaced relation with their angles directed towards the mechanism chamber 14 and bisected by the longitudinal center line of the device. The angular guide members 20, 22 have projecting from their vertices, upper and lower anchorage members 26, 28 directed outwardly of the magazine chamber, so that, in the assembled condition of the device, said anchorage members extend into the mechanism chamber 14. The free ends of the anchorage members have slots 26', 28' formed in them which are adapted to receive anchoring

rings 30 (Fig. 2) attached to rubber bands 32 which partially embrace a bundle 24 of toothpicks, shown in Fig. 2 as of the flat type, although it is to be understood that our dispensing device may also be used for round type toothpicks or for bundles made up of both types intermixed. The elastic bands 32 act to urge the bundle against the inner faces of the angular guide members 20, 22, whereby the bundle which normally is of substantially cylindrical contour is deformed to conform with the angular portion of the guide members in contact with the bundle.

The rubber bands 32 are positioned on the bundle so that the one band lies below the upper angular guide member 20 and the other band lies above the lower angular guide member 22, when the bundle is introduced into the magazine chamber, so that the bands lie clear of the base 16 and of the lid 15. To prevent the upper band from slipping down and also to ensure that it shall embrace as large a portion of the periphery of the bundle as possible, we provide a pair of projecting studs 34 on the upper anchorage member 28, directed away from the base 16. In charging the magazine, therefore, the bundle of toothpicks 24 with the bands 32 in position is placed in the magazine chamber 12, with the rings 30 facing in the direction of the anchorage members 26 and 28. The ring of the lower band is then taken, the band stretched and the ring slipped into the slot 28' of the lower anchorage member 28. Thereupon the ring of the upper band is taken, the band is stretched until it can pass over the upper anchorage member 26, the band being then positioned between the two studs 34 and the ring finally slipped into the slot 26'.

The magazine chamber likewise comprises a pair of compression arms 36, 36' secured to the free ends of a U-shape spring member 38 attached to the inner face of the side wall 17' as by means of supporting members 40, 40'. The compression arms project outwardly of the magazine chamber 12 between the upper and lower angular guide members and are inclined towards each other inwardly of the chamber 12. The arms 36, 36' are provided with inner contact surfaces 42, 42' and at their free ends with outwardly offset cam fingers 44, 44' and are adapted to be moved inwardly of the chamber on operation of the device as will hereinafter be explained. The arms 36, 36' may also be provided on their surfaces nearest to the side walls of the housing with resilient buffers 100 to deaden the knock which might be produced when the said arms are forced outwardly during the dispensing movement of the device as explained below.

When the magazine chamber is constructed to be separable from the mechanism chamber, as shown in the drawings, locking means may conveniently be provided for locking the magazine chamber to the mechanism chamber in the assembled condition of the dispensing device. For example, locking plates 94 may be provided fixed to the free ends of the legs of T-shape resilient members 96 secured to the inner surfaces of the side wall 17' of the magazine chamber. The locking plates 94 are arranged to project beyond said side wall and to engage in slots 98 formed in the side wall 17 of the mechanism chamber 14.

The lid 15 of the device consists of a thick portion 74 and a thin portion 76, which latter is formed by recessing the inner surface of the lid over an area substantially equal to that defined

by the side wall 17' and the upper angular guide member 20 of the magazine chamber, and is perforated to provide a narrow dispensing orifice 92 located so that in the assembled condition of the device, said dispensing orifice will lie over the angle defined by the vertices 20', 22' within said magazine chamber 12. The thick portion 74 has near the end remote from the magazine chamber an opening 80 through which a hollow actuating plunger member 62 is adapted to pass freely. One end of said plunger member is outside the mechanism chamber and has a threaded portion 64 (Fig. 6) adapted to receive a button 66. At its other end the plunger member 62 has secured to it a cam member 54 having a curved portion 60 partially embracing the plunger member, and a pair of wings 55, 55' which in the assembled condition of the device project towards the magazine chamber. Said wings are inclined towards each other both horizontally or cross-wise of the cam member 54 and vertically or towards the vertical plane through the longitudinal center line of the device, and have cam surfaces or edges 58, 58' respectively, extending between the upper and lower edges of the cam member. Thus the gap between the upper free corners of the wings 55, 55' is narrow enough to cause the cam fingers 44, 44' to move to their position of greatest approximation, as will be hereinafter explained, while still of sufficient width to clear the upper anchorage member 26 and its associated rubber band, whereas the gap between the lower free corners of said wings is considerably wider.

The cam member 54 is strengthened internally by a bridge piece 56 to which a dispensing finger 52, having a flat 52' formed on its free end, is adjustably secured as by nuts 53 (Figs. 2 and 3). The cross-bar 51 of the bridge piece 56 may, if necessary, be cut back as shown at 49 so as to allow the cam member 54 to pass beyond the upper anchorage member 26 during the upward travel of the plunger member 62. The plunger member 62 is adapted to move slidably over a guide rod 68 secured as by screwing, to a base plate 70 fixed to the bottom wall 16 of the housing and disposed on the center line thereof against the curved portion of the side wall 14. A compression spring 72 surrounds said guide rod 68 and urges the plunger member 62 and the attached cam member 54 and dispensing finger 52 towards the lid 15 of the housing. Said lid may be provided on its inner surface with a resilient cushion 90 (Fig. 7) to deaden the knock produced by the striking of the cam member against the lid. Said cushion may conveniently be secured to the lid by angle iron fastening members 82, 82', having tapped holes 84 adapted to receive securing screws 86 (Fig. 1) passing through corresponding holes 88 (Fig. 5) in the side wall 17, for normally securing the lid to the housing. If desired the screws 86 may be sealed or otherwise protected from unauthorized interference.

To prevent the dispensing finger 52 from accidentally swinging out of alignment with the vertices of the angular guide members 20, 22, we provide lateral limit members 50 extending longitudinally of the housing from transverse brackets 46, 46'. Said limit members may have extending therefrom intermediate stop members 48, 48' adapted to bear against the bundle of toothpicks at points intermediate the angular guide members 20, 22. Each stop member will therefore be parallel to and vertically aligned with an arm of the angular guide members.

If the dispensing device be taken in the assembled condition shown in Fig. 1, it may be charged by pressing the locking plates 94 inwardly until they disengage the slots 98, and withdrawing the magazine chamber 12. A bundle of toothpicks, previously prepared and held together by rubber bands such as 32, with the rings 30 alined longitudinally of the bundle, is then inserted in the magazine chamber between the side wall 17' and the angular guide members 20, 22. The bands 32 are then stretched and the rings anchored as previously explained and the magazine chamber reassembled to the mechanism chamber. When the magazine chamber is so reassembled, the compression arms 36, 36' extend into the mechanism chamber passing between the transverse brackets 46, 46', so that the cam fingers 44, 44' lie vertically below the free edges 58, 58' of the wings 55, 55' of the cam member 54, which will be held at the upper end of its stroke, against the lid 15 by the action of the spring 12.

To extract a toothpick, it is necessary to depress and then release the plunger 62. Depression of the plunger causes the cam member 54 to be moved downwardly past the cam fingers 44, 44', the dispensing finger 52 likewise moving down between the limit members 50. The length of the dispensing finger is such that it projects into the magazine chamber slightly beyond the vertices of the angular guide members and is thus in contact with the periphery of the bundle 24.

As the cam member 54 moves down, the cam surfaces or edges 58, 58' contact the faces of the cam fingers 44, 44' nearest to the side wall 17 of the housing, and owing to the inward inclination of said cam edges, cause the compression arms 36, 36' to approach one another, thus causing the contact surfaces 42, 42' to squeeze that part of the bundle 24 lying nearer to the mechanism chamber. The parts are so arranged that the said contact surfaces push the major portion of the bundle towards the magazine chamber and also thin down the portion lying within the vertices of the angular guide members 20, 22, so as to present one single toothpick to the free end of the dispensing finger 52. Maximum compression of the bundle takes place when the plunger member 62 is just about to reach the end of its down stroke. As the plunger reaches the limit of its down stroke, the upper portion of the cam edges 58, 58' clears the cam fingers 44, 44', thus allowing the compression arms 36, 36' to spring apart and release the bundle, and at the same time take up a position between the upper edges of the wings 55, 55' and the side wall 17 of the housing.

On releasing the plunger, it together with the cam member 54 and the dispensing finger 52, is moved upwardly by the action of spring 12, the wings 55, 55' passing between the compression arms 36, 36' and forcing these apart to relieve the bundle 24 of all pressure except that of the rubber bands 32, which is sufficient to hold the single toothpick (presented to the dispensing finger as described with reference to the down stroke of the plunger), against said dispensing finger with sufficient pressure to allow the finger to push up said single toothpick, and to cause the toothpick to be guided by the angular guide members so as to pass through the dispensing orifice 92. The toothpick is not ejected through said orifice but merely raised so that it protrudes a sufficient distance to enable it to be

seized and removed from the dispensing device by hand. The resilient buffers 100 prevent any undesirable noise or clicks being produced when the arms 36, 36' are forced apart.

5 When the plunger and its associated parts are about to reach the upper limit of their travel, the wings 55, 55' clear the cam fingers 44, 44' thus permitting the compression arms 36, 36' to move into their original position under the action of spring 38, so as to lie within the path of travel of the lower portions of said wings.

If desired the device may have a felt, cork, rubber or the like damping coating 102 applied to the outer side of the bottom wall 16, 16'. Likewise a lightly spring pressed cover (not shown) may be provided for the dispensing orifice as will be readily understood by those skilled in the art to prevent the entrance of dust through said orifice when the device is not in use.

20 We claim:

1. A dispenser for toothpicks or the like comprising a container having an aperture through which a toothpick may pass from the interior to the exterior thereof, angular guiding means for limiting the disposition of toothpicks within said container, means for yieldably holding a quantity of toothpicks in a deformable bundle against said guiding means whereby to impart an angular shape to one side of such a bundle, a reciprocating dispensing finger adapted to engage a toothpick located at the vertex of said side of such bundle and to move said toothpick longitudinally to a point where it protrudes through said aperture and beyond the confines of said container, a pair of compression arms disposed at opposite sides of said vertex, a cam device constrained to reciprocate with said dispensing finger and adapted to engage said compression arms and urge the latter together, on the non-dispensing stroke of said finger, whereby to cause said arms to press and deform said bundle to narrow said vertex, and operating means, operable from the exterior of the dispenser, for effecting reciprocation of said finger and said cam device.

45 2. A dispenser for toothpicks or the like comprising a container having an aperture through which a toothpick may pass from the interior to the exterior thereof, angular guiding means for limiting the disposition of toothpicks within said

50 container, means for yieldably holding a quantity of toothpicks in a deformable bundle against said guiding means whereby to impart an angular shape to one side of such a bundle, a reciprocating dispensing finger adapted to engage a toothpick located at the vertex of said side of such bundle and to move said toothpick longitudinally to a point where it protrudes through said aperture and beyond the confines of said container, a pair of resiliently mounted compression arms disposed at opposite sides of said vertex, a pair of cams constrained to reciprocate together and with said dispensing finger and adapted to engage said arms and urge the latter together, on the non-dispensing stroke of said finger, whereby to cause said arms to press and deform said bundle to narrow said vertex, and a plunger, operable manually from the exterior of the dispenser, and adapted to reciprocate said cams and said dispensing finger.

60 3. A dispenser according to claim 2, the said compression arms being so disposed at an intermediate point in the stroke of said cams that the cams are disengaged from said arms at the beginning of the non-dispensing stroke of the dispensing finger, are in pressure-establishing en-

70

65

gagement with said arms during a part of the non-dispensing stroke of said finger whereby to narrow the vertex of the bundle of toothpicks, and are disengaged from said arms at the end of said non-dispensing stroke whereby to release the pressure on the bundle of toothpicks prior to the dispensing stroke of the dispensing finger so that the toothpick engaged by the latter may be moved easily to a position in which it protrudes from said aperture.

4. A dispenser according to claim 2, the said compression arms being disposed at an intermediate point in the stroke of said cams and each of said pair of cams having two camming surfaces, one said surface being adapted to engage a compression arm on the non-dispensing stroke and press said arm toward and into engagement with the bundle of toothpicks whereby to narrow said vertex and the other said surface being adapted to engage said compression arm on the dispensing stroke and urge said arm away from said bundle whereby to release the pressure on the latter so that a single toothpick may be slid easily by the dispensing finger to a position in which it extends through the aperture in the container.

5. A dispenser according to claim 2, the said cams, dispensing finger, and plunger all being rigidly connected as a unitary structure, the said plunger being hollow, the container having a post therein rigidly fixed to the bottom thereof, the post extending into said plunger to guide the latter, and a spring coacting with the container and said plunger and adapted to move said plunger through the dispensing stroke thereof after the manual movement of said plunger through its non-dispensing stroke and to hold the plunger yieldably in position at the end of its dispensing stroke.

6. A dispenser according to claim 2, the said container comprising two separable sections, one being a magazine section having associated therewith the said guiding means, toothpick holding means, and compression arms, and the

other section being a mechanism section, having associated therewith the said dispensing finger, the said pair of cams and the said plunger; and, when the two said sections are assembled, the 5 said cams and finger being constrained to reciprocate parallel to a toothpick at the said vertex, and disposed to coact respectively with the said compression arms whereby to narrow the said vertex and with a toothpick whereby to dispense 10 the latter.

7. A dispenser for toothpicks or the like, comprising a container having two separable sections, one being a magazine section and the other being a mechanism section, the said magazine 15 section comprising a pair of spaced-apart angular guide members, anchorage members fixed upon said guide members and extending outwardly from the angle thereof, resilient members adapted to encircle a bundle of toothpicks and 20 to be fastened upon said anchorage members whereby to press said bundle against the inner sides of the guide members and impart an angular shape to one side of such bundle, and compression arms disposed at opposite sides of the 25 vertex of the angular side of said bundle; and the said mechanism section comprising a reciprocating finger, adapted to engage and dispense a toothpick disposed at the said vertex, a pair of cams adapted to engage and press said compression arms against the bundle whereby to narrow 30 said vertex, a plunger for operating said finger and cams in unison and a pair of vertical wings which when the said sections are assembled, are disposed between said angular guide members, 35 and extend substantially in planes common to said members whereby to assist in supporting the bundle of toothpicks against the tension of the said resilient members, the parts in both said sections being so arranged that they assume the proper operating relationship when the two said sections are moved together in a common straight line when being assembled.
